POCKET CUTLERY HOLDER

Charles T. Shatzer, Zullinger, Pa.

Application January 27, 1948, Serial No. 4,480

3 Claims. (Cl. 206—75)

1

This invention relates to a container designed for containing spoons, forks and knives, some of which have exceptionally sharp edges.

The primary object of the invention is to provide a container of this character which is in the form of a tray, the members of which container having pockets for the reception of the blades of sharp knives, so that the sharp edges of the knives will be protected from being dulled and to prevent damage to the hands of a person removing knives or articles from the container.

An important object of the invention is to provide a container of this character wherein the side walls and partitions are so constructed that the sharp-edged knives will fit therein and be protected without usurping space for general cutlery.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

Referring to the drawing:

Figure 1 is a plan view of a container, constructed in accordance with the invention.

Figure 2 is a side elevational view thereof, a portion of one of the sides of the container having been broken away.

Figure 3 is a sectional view taken on line 3—3, Fig. 1.

Figure 4 is an end elevational view of the container, a portion of the end wall having been broken away.

Referring to the drawing in detail, the body portion of the container, is in the form of a tray embodying side walls 5, 6 and 7 and a longitudinal partition 8 dividing the tray into lateral compartments 9.

The partition 8 connects with the partition 10 that extends transversely of the body of the tray defining a compartment 11 for spoons and forks or knives which are not provided with exceptionally sharp edges.

The side walls 5 are formed with cut-out portions 12 which cut-out portions are inclined downwardly towards the center of the tray, providing clearances for handles of knives. The side walls 5 are also provided with grooves 13 that extend from the cut-out portions 12, to portions adjacent to the end wall 7 of the tray. These grooves are designed to receive the sharp blades of large knives such as carving knives or the like, the bottoms of the grooves being curved

2

as at 14 so that the curved sharp edges of the knives may rest therein.

The longitudinal partition 8 is also formed with a groove 15 that extends from the inner end of the cut-out portion 16 of the partition, the groove 15 being designed to accommodate the blade of a smaller knife, while the cut-out portion 16 accommodates the handle.

The partition 10 is also formed with a groove 17 to receive the blade of a small knife, while the cut-out portion 18 accommodates the handle. This structure is also duplicated in the end wall 6, which is designed to receive the blade of a small but exceptionally sharp knife.

From the foregoing it will be seen that due to the construction shown and described, I have provided a tray which has been designed to receive knives, forks and spoons, and at the same time provides pockets for the blades of exceptionally sharp knives, such as butcher knives or the like to protect them from being dulled and to protect a person against cutting the hands when when removing spoons or forks from the compartments of the tray, providing this service without usurping space for general cutlery.

What is claimed is:

1. A tray of the class described, comprising side walls and partitions dividing the tray into compartments, and said side walls and partitions having grooves formed in the upper edges thereof, said grooves providing pockets for knife blades and said side walls and partitions having cut-out portions extending to the grooves, adapted to accommodate the handles of the knives held in the grooves.

2. A tray of the class described, comprising side walls and partitions dividing the tray into compartments, said side walls and partitions having grooves formed in the upper edges thereof, and having cut-out portions extending from the grooves to certain of the ends of the side walls and partitions, providing compartments for the handles of knives, the blades of the knives being held in the grooves, and said grooves having curved bottom walls conforming to the curvature of the knives positioned within the grooves.

3. A tray of the class described, comprising a body, partitions dividing the body into compartments, said body walls and partitions having pockets shaped to conform to the shape of knife blades, and adapted to receive the knife blades, said body walls and partitions also having cut-out portions adapted to accommodate the handles of the knives held within the pockets.
